CLAIM

The ornamental design for a toothbrush handle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view showing the front and right side of a first embodiment of a toothbrush handle showing our new design;

FIG. 2 is a front view thereof;

FIG. 3 is a left-side view thereof;

FIG. 4 is a rear view thereof;

FIG. 5 is a right-side view thereof;

FIG. 6 is an enlarged top view thereof;

FIG. 7 is an enlarged bottom view thereof;

FIG. 8 is a perspective view showing the front and right side of a second embodiment of a toothbrush handle;

FIG. 9 is a front view thereof;

FIG. 10 is a left-side view thereof;

FIG. 11 is a rear view thereof;

FIG. 12 is a right-side view thereof;

FIG. 13 is an enlarged top view thereof;

FIG. 14 is an enlarged bottom view thereof;

FIG. 15 is a perspective view showing the front and right side of a third embodiment of a toothbrush;

FIG. 16 is a front view thereof;

FIG. 17 is a left-side view thereof;

FIG. 18 is a rear view thereof;

FIG. 19 is a right-side view thereof;

FIG. 20 is an enlarged top view thereof; and,

FIG. 21 is an enlarged bottom view thereof.
